UNITED STATES PATENT OFFICE.

FREDERICK WRIGLEY AND JAMES ROBERTSON, OF BURY, COUNTY OF LANCASTER, ENGLAND.

MACHINERY OR APPARATUS TO BE USED IN THE MANUFACTURE OF PAPER, WOOD PULP, AND OTHER KINDRED INDUSTRIES.

SPECIFICATION forming part of Letters Patent No. 276,989, dated May 1, 1883.

Application filed January 11, 1883. (No model.) Patented in England November 1, 1882, No. 5,201.

To all whom it may concern:

Be it known that we, FREDERICK WRIGLEY and JAMES ROBERTSON, citizens of the United Kingdom of Great Britain and Ireland, residing at Bury, in the county of Lancaster, England, have invented certain new and useful Improvements in Machinery or Apparatus Used in the Manufacture of Paper, Wood Pulp, and other Kindred Industries; and we do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

Our invention, which relates to machinery or apparatus used in the manufacture of paper, wood pulp, and other kindred industries, has reference to the section or class of such apparatus known as the "jog" knotter or strainer; and our invention has for one of its objects to render the movement or action of the said knotter or strainer equal over all its surface, whereby the slits are prevented from filling up and the knotter or strainer plates are worn evenly and equally, and therefore pass a larger quantity of pulp in relation to the gage of plate or sieve used.

Our invention has also for its object to extract surplus water from the pulp after it has been strained and before it reaches the paper-making-machine wires, thereby lessening the tear and wear on the said wires and causing them to last much longer.

And in order that our said invention may be properly understood, we now proceed more particularly to describe the system, mode, or manner in or under which it is or may be used or carried out in practice, reference being had to the annexed drawings, and to the letters and figures marked thereon—that is to say:

On the sheet of drawings hereunto appended, Figure 1 is a longitudinal section, and Fig. 2 a transverse section, of the improved jog knotter or strainer constructed in accordance with our said invention; and, as shown by these figures, the improved knotter or strainer con-

sists of the ordinary vat, A, and strainer-plate frame B, the said vat being mounted on vertical standards or frames C.

Underneath the vat A a shaft, D, is placed horizontally, on which are keyed stepped cams or tappets E and a driving-pulley, F, by a belt passed round, which motion is communicated to the shaft D from any suitable prime mover; or, instead of the stepped tappets or cams E, eccentrics, cranks, or other equivalents may be used. This action may be communicated also from a shaft or shafts working either above or below or at the side of the strainer; but we prefer the arrangement as shown on the drawings and stated above, the principle being the same in all—that is to say, the rapid and simultaneous perpendicular jog or action given to the whole surface of the knotter or strainer.

At or near each end the shaft D is supported in brass or other suitable bearings, a; securely fixed in boxes G, which latter are connected together by a pipe or tube, H, through which the shaft D passes. The boxes G and the pipe or tube H thus form one continuous chamber containing the principal moving parts of the apparatus; and as the chamber is filled with oil, tar, or other equivalent lubricant, preferably to the level of the covers I of the boxes G, the friction, tear, and wear on these parts are reduced to a minimum.

The strainer-plate frame B is supported by vertical rods J, whose lower ends are in contact with the stepped cams or tappets E, a rigid connection between the frame and the rods J being effected by the cotters or keys b, while the said rods are at the same time free to move vertically through the sleeves or guides L. The strainer-plate frame B is hinged at M, and the horns or brackets N, by which the frame is attached to the vertical rods J, are each formed with a slot, as indicated at e, Fig. 2, so that on withdrawing the cotters or keys b the frame may be tilted or raised up in the usual manner. When in the position shown on the drawings the frame B may fall on or jog against pads fixed to the flange of the vat A underneath the horns or brackets N; or, and as is preferred, it may drop upon the upper ends of the two top guides, L; and the amount

of jog given to the said knotter or strainer-plate frame is regulated by wedges P, on which the boxes G are carried. The wedges P are capable of being moved in a horizontal plane by the screws d, and when the jog has been regulated they are securely fixed in position by the screw-bolts e.

By constructing and operating the jog knotter or strainer substantially as hereinbefore described the whole surface of the strainer-plates is available for straining the pulp, the tear and wear on the moving parts are reduced to a minimum, and the apparatus is practically noiseless.

Our improved mode of action, as hereinbefore described, also permits of an increase in the number of jogs per minute far in excess of anything hitherto produced, each jog still being distinct and separate. Therefore, as each distinct jog passes a certain quantity of stuff, it naturally follows that the efficacy of the strainer relatively to the area of the plates or sieves employed is increased, and the space required for strainer-surface is less in proportion to the work done than in the case of any other machine of a similar class. The pulp, on leaving the vat A and on its course to the machine-wires, flows in the direction of the arrows, Fig. 1, over the surface R to the inclined frame S, which is perforated or covered with wire-cloth of any required degree of fineness, in passing down which the pulp parts with the surplus water, and then falls into the breast-box T, from whence it passes to the wires in the usual manner. The surplus water extracted from the pulp on the inclined frame S falls into the box or tank U, and may be drawn off as desired.

We are aware that it is not new to construct paper-pulp screens with a vertical jogging motion operated by means of a revolving tappet,

and provided with a regulating wedge or wedges; and we do not broadly claim these features.

Having now described and particularly ascertained the nature of our said invention and the manner of carrying it into practical effect, what we desire to claim and secure by Letters Patent is—

1. In a paper-pulp washing and straining apparatus, the combination of the vat A, vertical standards C, strainer-plate frame B, vertical rods J, keys b, brackets N, hinge M, slot c, and the tappets E, having a shaft, D, and the wedges P, having screws d, as and for the purposes set forth. 50

2. In a paper-pulp washing and straining apparatus, the continuous lubricating chamber surrounding the axle and tappets for the diminishment of noise and wear and tear of the machine, as described. 55

3. In conjunction with knotters and strain-ers for paper-pulp, the combination and ar-rangement of apparatus for extracting the sur-plus water after the pulp has been strained, substantially as hereinbefore described and 60 shown. 65

In testimony whereof we, the said FREDERICK WRIGLEY and JAMES ROBERTSON, have hereunto set our hands and seals this 22d day of December, 1882.

FREDERICK WRIGLEY. [L. S.]
JAMES ROBERTSON. [L. S.]

In presence of—

W. WARDLE,

Clerk with Messrs. Rowley, Page & Rowley, So-
licitors, 2 Clarence Buildings, Booth Street,
Manchester.

ED. LAMB SCOTT,
Clerk to E. Butler Rowley, Notary Public, Man-
chester.
